(57) **CLAIM**

The ornamental design for a handle controller for a heat press, as shown and described.

DESCRIPTION

FIG. 1 is a top perspective view of a handle controller for a heat press;

FIG. 2 is a top view of a handle controller for a heat press; FIG. 3 is a side view of a handle controller for a heat press; FIG. 4 is a front view of a handle controller for a heat press; FIG. 5 is a back view of a handle controller for a heat press; FIG. 6 is a bottom perspective view of a handle controller for a heat press;

FIG. 7 is a top perspective view of a handle controller for a heat press;

FIG. 8 is a bottom perspective view of a handle controller for a heat press; and,

FIG. 9 is a front view of a handle controller for a heat press. The broken lines in the figures depict portions of the handle controller for a heat press that form no part of the claimed design.

1 Claim, 7 Drawing Sheets
